UNITED STATES PATENT OFFICE.

JAMES BARNES, OF NEW KENSINGTON, PENNSYLVANIA, ASSIGNOR OF ONE-HALF TO
SEWARD R. SEYBOLD, OF NEW KENSINGTON, PENNSYLVANIA.

APPARATUS FOR MAKING SHEET-GLASS.

1,247,617.

Specification of Letters Patent. Patented Nov. 27, 1917.

Application filed March 21, 1917. Serial No. 156,249.

To all whom it may concern:

Be it known that I, JAMES BARNES, a citizen of the United States, and resident of New Kensington, Westmoreland county, 5 Pennsylvania, have invented a new and useful Improvement in Apparatus for Making Sheet-Glass, of which the following is a specification.

This invention relates to an apparatus for 10 making sheet glass, particularly to an apparatus designed to perform the method described and claimed in co-pending application Serial No. 155,228 filed March 16, 1917.

The object of the invention is to provide 15 an apparatus in which a batch of glass raised to a high temperature may be subjected by a continuous operation to successive drawing, forming, smoothing, polishing, and annealing, and in which the glass is 20 drawn and formed in a flat sheet without the necessity of forming cylinders or of pouring the glass. A further object of the invention is to provide an apparatus in 25 which the actuating parts may be run at a uniform rate of speed so that the glass may be carried therethrough and turned out as a finished product by an uninterrupted cycle of operations. A still further object of the invention is to provide in such 30 an apparatus, special means for completing the formation of a flat glass sheet and for simultaneously smoothing and polishing the same, such means being so designed, and provided with rubbing surfaces of such a 35 nature, that a maximum smoothing and polishing effect is provided, and the surfaces arranged to contact with the glass, for smoothing and polishing the same, are protected from excessive deterioration due to 40 the heat of the glass rubbing thereagainst. A still further object of the invention is to so arrange the rubbing and polishing means 45 that the rubbing surfaces may be readily renewed without unduly interrupting the operation.

In the accompanying drawings, Figure 1 is a central vertical section through the apparatus; Fig. 2 is a plan view of the same

with the roofs of the furnace and of the leer removed; Fig. 3 is a vertical cross section 60 of the rubber for smoothing and polishing the glass; Fig. 4 is an elevation of the same; Fig. 5 is a longitudinal vertical section through the same; Fig. 6 is a broken side view showing two of the sprockets and 65 one chain of the leer conveyer; and Fig. 7 is a detail view showing the construction of the conveyer bars.

Briefly described, the elements of the apparatus comprise a furnace 1, a cooling 60 chamber 2 adjacent the discharge opening of the furnace, a pair of vertically disposed adjustable rolls 3 adjacent the discharge opening of the cooling chamber, rubber 4 located forwardly of the rolls 3, a pair of 65 vertically disposed adjustable rolls 5 located forwardly of the rubber 4, and a leer comprising a heated chamber 6 and a cooling chamber 7 located forwardly of the 70 wheels 5.

The furnace 1, which is preferably of such nature as to raise the batch of glass therein to a high temperature, is provided with a discharge opening 8 having a drop gate 9 adjustable by means of chain 10, 70 block 11, and windlass 12, so that it serves to completely close the opening 8, or to regulate the width of the aperture for the outflow of the molten glass from the furnace. Immediately adjacent the discharge 75 opening 8 of the furnace is a cooling chamber 2 having a floor 13 so formed as to provide a broad flat surface for the cooling of the molten glass from the furnace in its passage through the chamber. The discharge opening of the chamber 2, at the forward extremity thereof, is provided with a drop gate 14 similar to that used to close the discharge opening of the furnace, the 80 position of the drop gate being also regulated by means of chain 15, block 16, and windlass 17 so that it may be adjusted to form a narrow aperture between its lower extremity and the floor 13 of the chamber. Adjacent the discharge opening of 85 the cooling chamber are the vertically dis-

posed rolls 3 mounted in standards 18 provided with adjusting screws 19 for regulating the relative position of the rolls.

The rubber 4 comprises a lower casing 20 mounted on a truck 21 arranged to run on a track 22, and an upper casing 23, both of these casings being provided with projecting solid blocks 24, 24^a formed of wood, wood fiber, or other suitable material for smoothing and polishing the glass. The blocks 24, 24^a are rigidly secured in each of the casings by means of bolts 25 passing through the walls of the casings into the bodies of the blocks; and each of the casings 16 is so formed as to provide a receptacle for water which extends completely around the portion of the block which projects into the interior of the casing, and provides a water jacket the water in which tends to percolate 20 through the bodies of the blocks to keep the same continually moist. The casings 20 and 23 are secured together in relatively adjustable position by means of set screws 26 having a screw-threaded engagement in lugs 25 27 and 28 projecting from each of the four corners of the upper casing 23 and of the truck 21 respectively. The lower casing 20 has secured thereto a pair of guards 29 so arranged as to prevent material passing between the blocks 20 from escaping past the sides of the rubber. Secured to the upper portion of the casing 23 is a flexible connection 30 passing through block 31 on a carriage 32 arranged to run on a transversely 36 extended overhead track or way 33.

The wheels 5 are mounted in standards 34 similar to those in which rolls 3 are mounted and are likewise provided with similar adjusting screws 35. Forwardly of the wheels 46 5 is a leer comprising the heated chamber 6 provided with a plurality of suitable gas burners 36 and the cooling chamber 7, forwardly of which is located a cutting table 37. Extending completely through both of 45 the chambers 6 and 7 is an endless chain conveyor formed of transversely extending bars or slats 38 connected at their extremities to endless chains 39, which pass over a pair of sprockets 40 mounted on a shaft 41 50 at the forward extremity of the leer and over a pair of sprockets 42 mounted on a shaft 43 at the rearward extremity of the leer. This conveyor is positively actuated by being connected with an electric motor 55 or other suitable prime mover, such motor and connections not being shown. Mounted on the shaft 43 at the rearward extremity of the leer are sprockets 44 and 45 over which pass sprocket chains 46 and 47, these 60 chains also passing over sprockets 48 and 49 on the shafts of the lower roll 3 and the lower pair of wheels 5 respectively. By this means the lower members of both rolls 3 and wheels 7 are positively actuated at an equal rate of speed with the conveyor of the leer,

the upper members of both rolls and wheels being preferably idlers. The bars 38 of the conveyer of the leer are preferably formed with a metal core 50 and an asbestos cover 51, as shown in Fig. 5 of the drawings, so that glass passing through the leer may rest thereon without danger of being scratched and without chilling such as would occur from contact with a metallic surface. The conveyer is preferably provided with a pair 75 of riders 52 arranged to support the bars 38 forming the upper portion of the conveyer.

In use of the apparatus the door 9 of the furnace is raised to allow a stream of molten glass, which is preferably in as high a state of fluidity as possible, to flow down the surface 13 forming the floor of the cooling chamber 2. In case the glass does not readily flow it may be drawn initially from the furnace by a hook or other suitable means. The door 14 of the cooling chamber is so adjusted relatively to the floor thereof, that glass drawn between its lower extremity and the floor of the cooling chamber will take 90 the approximate form of a flat sheet, it being understood that the glass is in a viscous and thoroughly cohesive state at the time when it is drawn from the cooling chamber. At the beginning of the operation, the rolls 25, rubbing blocks 24, 24^a, and wheels 5 are raised and the roughly formed glass sheet is drawn therethrough by any suitable means, such as a clamp arranged to be fastened to the extremity of the sheet of glass and 100 hooked over one of the bars 38 of the leer conveyer as shown and described in co-pending application Serial No. 155,228, filed March 16, 1917, the conveyer and the rolls 3 and wheels 5 being set in motion with the 105 beginning of the operation of drawing. As the sheet of glass is drawn through the apparatus the rolls 3, rubbing blocks 24, 24^a, and wheels 5 are successively brought to bear upon it, so that by the time a fair proportion of glass rests upon the conveyer of the leer all the elements of the apparatus will be performing their functions in drawing or forming the sheet of glass. During 110 the continuance of the operation after it is 115 under way, the glass is drawn from the furnace and cooling chamber by means of the engagement of the rolls 3 and wheels 5 thereon, particularly by the engagement of the latter, so that during this continuance 120 it is merely necessary to maintain the parts in properly adjusted position. By this means a continuous sheet of glass 53 is formed and is passed through the leer where it is subjected to an annealing treatment, 125 and from which it is passed on to the cutting table 37 and there cut into suitable lengths. For the sake of convenience both the heated chamber and the cooling chamber 130 of the leer are shown as of much less length

relative to the remainder of the apparatus than is desirable in actual practice, since although the rate of drawing and travel of the glass is necessarily slow, the leer must 5 be of considerable length in order to secure an effective annealing treatment.

The casings 20 and 23 of the rubber 4 are so adjusted that the space between the rubbing blocks 24 and 24^a will be the thickness 10 desired for the completed sheet. Since the glass is still at a high heat when reaching the rubber the action of the blocks serves to determine the thickness of the sheet and also smooths and polishes the same, the 15 blocks being so moistened by means of the water jackets of the casings that their surfaces contacting with the heated glass do not burst into flame, and do not quickly become so charred as to destroy their usefulness. 20 Where wooden blocks are used, as is preferable, a slight charring of their rubbing surfaces is desirable since this gives the surfaces a fine velvety finish which is particularly desirable in polishing the glass. 25 As the blocks burn away the upper casing 23, with the upper rubbing block rigidly secured therein, may be adjusted downwardly by means of set screws 26. When the 30 surfaces of the blocks become too deeply charred, the operation is momentarily stopped, the rubber 4 is removed from position and a similar rubber is substituted. In removing the rubber the set screws 26 may be completely withdrawn from the lower 35 casing 20 and the upper casing 23 lifted by means of its connections with the carriage 32, so that the upper casing may be raised and removed from the zone of operations on the track 33, at the same time that the 40 truck 21 carrying the lower casing is run out of position on the track 22. The rubbing surfaces of the blocks may then be scraped to bring them again into serviceable condition, and the position of the blocks 45 in the casings may be adjusted by removing the bolts 25 and inserting them again at such points as to increase the proportion of each of the blocks projecting from its casing. When the blocks have been too 50 much burned for further use, they may be removed completely from the casings in the manner above described and fresh blocks may be substituted.

The product produced by the apparatus 55 described is superior to window glass which is drawn in cylinders, since the constructions and bulges which are apt to occur to a greater or lesser extent in the cylinder method have the effect of making a sheet in 60 which waves are formed and in which the product is in other ways not uniform. This disadvantage is obviously overcome by the use of the described apparatus. The economy of operation is also considerable, since

the glass is submitted to a continuous working 65 which produces a finished product, or at least one which requires only a slight additional polishing of the glass before being placed upon the market.

Since it is possible to use the narrow aperture 70 between the floor of the cooling chamber and the lower extremity of its door and the flattening effect of the floor of the cooling chamber and even of the door of the furnace itself in partially forming the 75 sheet a sheet is brought into its finished form so gradually that the glass is not subjected to a violent working at any stage of the operation. It is to be understood, however, that the rubbing blocks perform the 80 final and chief operation in bringing the sheet to form as well as in removing any irregularities in the surface of the sheet and in polishing it. If a previously formed sheet of glass is to be freed of irregularities 85 and polished, it is obviously possible to use the rubber for smoothing and polishing the same. In such case the actuating elements of the apparatus shown, or other suitable means, may be used for passing the glass to 90 be heated between the rubbing blocks.

It is obvious that a considerable number of modifications in and additions to the apparatus may be made without departing from the spirit of the invention. As an example of such additions, additional means 95 for supporting the sheet, means for reheating the same during its passage from the furnace to the rubber, or mechanical means for vertically adjusting the lower block 100 supporting casing may be provided.

What I claim is:—

1. Apparatus for making sheet glass comprising a furnace, a rubber having relatively adjustable casings forming water jackets and solid wooden blocks in said casings, cooling means adjacent the discharge opening of the furnace for cooling glass withdrawn therefrom; and means for withdrawing molten glass from the furnace, 105 partially forming the same into a sheet, and passing it between the blocks of the rubber.

2. Apparatus for making sheet glass comprising a furnace, a rubber having relatively adjustable casings forming water jackets and solid wooden blocks in said casings, a leer; and means for withdrawing molten glass 115 from the furnace, partially forming the same into a sheet, and passing it between the blocks of the rubber and through said leer.

3. Apparatus for making sheet glass comprising a furnace, a rubber having relatively adjustable casings forming water jackets and solid wooden blocks in said casings, 125 cooling means adjacent the discharge opening of said furnace, a leer; and means for withdrawing molten glass from the furnace,

partially forming the same into a sheet, and passing it between the blocks of the rubber and through said leer.

4. Apparatus for making sheet glass comprising a furnace, a rubber having relatively adjustable casings forming water jackets and solid wooden blocks in said casings, a leer having a conveyer therein, rolls arranged to draw glass from the furnace and 10 pass it through the rubber onto the leer conveyer, and connections whereby said rolls and said conveyer may be actuated at an equal rate of speed.

5. Apparatus for making sheet glass comprising a furnace, a rubber having relatively adjustable casings forming water jackets and solid wooden blocks in said casings, cooling means adjacent the discharge opening of said furnace, a leer having a 20 conveyer therein, rolls arranged to draw glass from the furnace and pass it through the rubber onto the leer conveyer, and connections whereby said rolls and said conveyer may be actuated at an equal rate of 25 speed.

6. Apparatus for making sheet glass comprising a furnace, means for drawing glass from said furnace in a plastic condition and partially forming the same into a sheet; and 30 a rubber comprising a supporting frame and rubbing blocks movable on ways transversely disposed in the path of progression of said sheet, said ways and the parts of said rubber being so arranged that said rubbing 35 blocks may be brought to bear on said sheet or the rubber removed from position without affecting the position of the sheet in the drawing means.

7. Apparatus for making sheet glass comprising a furnace, means for drawing glass from said furnace in a plastic condition and partially forming the same into a sheet; and a rubber comprising a truck movable on ways transversely disposed in the path of 45 progression of said sheet, a rubbing block on said truck, and a second or upper rubbing block so mounted as to be vertically adjustable relatively to said truck and readily removable therefrom.

8. Apparatus for making sheet glass comprising a furnace, means for drawing glass from said furnace in a partially formed sheet; and a rubber comprising a truck movable on ways transversely disposed in the 55 path of progression of said sheet, a rubbing block on said truck, a second or upper rubbing block so mounted as to be vertically adjustable relatively to said truck and readily removable therefrom, and means whereby said upper block may be swung clear of said lower block and truck.

9. Apparatus for making sheet glass comprising a furnace, means for drawing glass from said furnace in a plastic condition and

partially forming the same into a sheet; and 65 a rubber comprising a truck movable on ways transversely disposed in the path of progression of said sheet, a rubbing block on said truck, a second or upper rubbing block so mounted as to be vertically adjustable relatively to said truck, an overhead way, and means connecting said upper block to said overhead way whereby said upper block may be swung clear of said lower block and truck. 75

10. Apparatus for making sheet glass comprising a furnace, means for drawing glass from said furnace in a plastic condition and partially forming the same into a sheet; and a rubber comprising a supporting 80 frame and casings forming water jackets movable on ways transversely disposed in the path of progression of said sheet, and wooden rubbing blocks of solid construction in said casings, said ways and the parts of 85 said rubber being so arranged that the rubbing blocks may be brought to bear on said sheet or the rubber removed from the path of the sheet without affecting the position of the latter in the drawing means. 90

11. Apparatus for making sheet glass comprising a furnace, means for drawing glass from said furnace in a plastic condition and partially forming the same into a sheet; and a rubber comprising a truck movable on ways transversely disposed in the path of progression of said sheet, a casing on said truck, a second or upper casing so mounted as to be vertically adjustable relatively to said truck and readily removable 95 therefrom, and wooden rubbing blocks of solid construction in said casings, said casings being so formed as to provide water jackets surrounding a substantial portion of 100 said blocks. 105

12. Apparatus for making sheet glass comprising a furnace, means for drawing glass from said furnace in a plastic condition and partially forming the same into a sheet; and a rubber comprising a truck movable on ways transversely disposed in the path of progression of said sheet, a second or upper casing so mounted as to be vertically adjustable relatively to said truck and readily removable therefrom, wooden rubbing blocks of solid construction in said casings, and means whereby said upper casing may be swung clear of said lower casing and truck, said casings being so formed as to provide water jackets surrounding a substantial portion of 110 115 said blocks. 120

13. Apparatus for making sheet glass comprising a furnace, means for drawing glass from said furnace in a plastic condition and partially forming the same into a 125 sheet; and a rubber comprising a truck movable on ways transversely disposed in the path of progression of said sheet, a casing

on said truck, a second or upper casing so mounted as to be vertically adjustable relatively to said truck, wooden blocks of solid construction in said casings, an overhead way, and means connecting said upper casing to said overhead way whereby said upper casing may be swung clear of said lower casing and truck, said casings being so formed as to provide water jackets sur-

rounding a substantial portion of said 10 blocks.

In witness whereof, I have hereunto set my hand.

JAMES BARNES.
